UNITED STATES PATENT OFFICE.

EDGAR F. HATHAWAY, OF WELLESLEY, MASSACHUSETTS, ASSIGNOR, BY MESNE ASSIGNMENTS, TO BARBER-COLMAN COMPANY, OF ROCKFORD, ILLINOIS, A CORPORATION OF ILLINOIS.

TEXTILE MACHINE.

Application filed July 10, 1916, Serial No. 108,388. Renewed October 18, 1922. Serial No. 595,462.

To all whom it may concern:

Be it known that I, EDGAR F. HATHAWAY, a citizen of the United States, and a resident of Wellesley, in the county of Norfolk and State of Massachusetts, have invented an Improvement in Textile Machines, of which the following description, in connection with the accompanying drawings, is a specification, like characters on the drawings representing like parts.

This invention relates to textile machines, being more particularly concerned with machines for selecting and separating warp threads and presenting them successively to the action of some mechanism, such, for example, as a thread placing device or member. For purposes of illustration, the invention is herein shown embodied in a warp drawing or thread placing machine where the thread placing device is utilized for placing the warp threads through drop wires, harness eyes and reed dents. While my invention has particularly advantageous application for a machine of this class, it is, however, susceptible of broad application to machines intended for other or similar purposes than drawing-in machines wherein the selection and separation of warp or other threads is required.

The character of the invention will be best understood by reference to the following description of an illustrative embodiment thereof, shown in the accompanying drawing, wherein—

Fig. 1 is an end elevation of a warp drawing machine constituting the preferred embodiment of my invention;

Fig. 2 is a front elevation of the left hand end of said machine;

Fig. 3 is a front elevation of the right hand end thereof;

Fig. 4 is a view partially in plan and partially in horizontal section upon the line 4—4 of Fig. 1, of the left hand end of the machine;

Fig. 5 is a similar view of the right hand end of the machine;

Fig. 6 is a detail, partially in end elevation and partially in vertical section, on an enlarged scale, of the means for driving the warp supports or carriages;

Fig. 7 is a detail in end elevation of a

portion of the means for driving the warp supports or carriages;

Fig. 8 is a front elevation of the construction shown in Fig. 7;

Fig. 9 is a detail in vertical section on the line 9—9 of Fig. 6;

Fig. 10 is a plan view of the pattern mechanism and the driving connections for certain of the parts, including the releasing keys, the drop wire feed worms, and the continuous driving means for the warp worms; and

Fig. 11 is a view in section on the line 11—11 of Fig. 10.

While the invention in many of its aspects is applicable to machines other than warp drawing machines and also to warp drawing machines of other types and constructions than that herein shown, I have herein illustrated the invention by embodiment in a well known type of drawing-in machine, which therefore need not be described in entire detail.

The machine here shown may, as to certain features thereof, be of the same general construction as the type of machine shown in British Patent No. 4,661 of 1904 and the United States Patent to Charles Lea, No. 1,153,869, dated September 14, 1915.

In the illustrated form of machine, as is well known to those skilled in the art, the heddles, warp threads and drop wires or other similar loom elements which may be and preferably are employed, are supported in a general parallel arrangement lengthwise the machine upon suitable supports carried by the main frame 1 of the machine. Any suitable thread placing device is provided. I have herein represented a drawing needle 2 adapted to be suitably reciprocated and carried by the traveling carriage 3, shown most clearly in Fig. 4. The said carriage with its needle is caused to traverse the extent of the reed which is or may be supported in the usual manner and is not herein indicated, and the extent of the heddles, which likewise have been omitted to permit clearness of illustration of other parts. The drawing needle is also traversed the extent of the drop wires if the latter be employed, such drop wires being of any suitable construction, not herein necessary

to disclose, and being similar if desired to those indicated in the copending application of Edward La Chance and Joseph Pennell, Serial No. 877,769, filed December 5, 1914 (now Patent No. 1,317,024, dated 70 September 23, 1919).

The needle carriage 3 is positively traversed through the machine by means hereinafter described, said means being operatively related to the main operating or drive shaft 4, whereby as hereinafter more fully set forth the needle carriage and the warp supports or carriages are positively and preferably differentially traversed 15 through the machine by means of operating connections from the said main drive shaft 4.

In the usual manner, the drawing needle 2 places successive warp threads through the 20 desired heddle eye, selected reed dent and drop wires, these being appropriately positioned for the purpose in the needle path by suitable selecting and positioning mechanism.

25 The drawing-in needle 2 may be operated in any suitable manner. In order to operate the same and the other portions of the mechanism, I have herein provided the main operating or drive shaft 4, which, as shown most clearly in Fig. 3, is provided with a driving pulley 5 receiving power from any suitable source. The said shaft is herein shown as provided with a clutch 6 and a brake 7. As shown most clearly in Fig. 1, 30 the shaft 4 is provided upon its left hand end with a sprocket gear 8 about which passes a sprocket chain 9 also passing about a sprocket gear 10 upon a shaft 11 having thereon change gear mechanism diagrammatically indicated at 12 and conveying motion to a short shaft 13. The shaft 13 is provided with a sprocket gear 14 about which passes a sprocket chain 15 also passing about a sprocket pinion 15' on a shaft 40 16, which in the disclosed embodiment of my invention is provided with two distinct and separate cams 17, 18, most clearly indicated in Fig. 8, and which may be relatively positioned as desired and of different extent 45 and contour, thereby to effect the independent control of the warp supports or carriages hereinafter referred to and at different rates of speed if desired.

50 The needle carriage 3 hereinbefore referred to as positively traversed through the machine is herein provided for that purpose with a divided nut 18' indicated in Fig. 4 and adapted to be placed through manual control or otherwise in suitable relation 55 with a thread 18'' upon the cam shaft 16, which thus constitutes a lead screw shaft for traversing the needle carriage through the machine and a cam shaft for effecting the traverse of the warp supports or carriages through the machine.

The means for thus positively and differentially operating the needle carriage and a warp supporting means broadly, may be that disclosed in the co-pending application of Field, Lanning, Hathaway and Blanchard, Serial No. 142,251, filed February 6, 1903 (now Patent No. 1,383,195, dated June 28, 1921), wherein, however, but a single warp supporting means was provided, for the single warp there disclosed. 70 75

The needle 2 may be operated in any suitable manner. As herein shown it is actuated from the main operating or drive shaft 4 through gearing indicated at 19 in Fig. 4 meshing with a gear splined and slidable on the main drive shaft 4, whereby is rotated the shaft 20 mounted upon the needle carriage and having thereon a crank wheel 21 connected by rod 22 with a lever arm 23, the lower end whereof is fulcrumed upon the needle carriage 3 and the upper end whereof is connected by a link 24 to the holder for the needle 2, whereby it is reciprocated in the suitable guide provided therefor. If desired and preferably I provide a needle 90 stripper indicated generally at 25 in Fig. 4 and suitably operated from the shaft 20 through a shaft 26, bevel gearing 27 and other parts not necessary to describe in detail. 95

The separate banks or groups of drop wires are supported or threaded upon longitudinally extending bars 28 shown in Fig. 4 as three in number. Any suitable number of drop wire supporting bars may be provided. They may be loom bars or special bars onto which the drop wires are transferred from the loom bars. I provide suitable releasing means for said drop wires and for that purpose have indicated in Fig. 4 shafts 29 provided with drop wire feeding worms 30, preferably of the general construction disclosed in the said application of La Chance & Pennell (now Patent No. 1,317,024). While the said shafts 29 may be 100 operated in any suitable manner so far as the broad purpose and scope of my invention are concerned, I preferably impart a movement of continuous rotation to each of said shafts instead of as heretofore intermittently rotating them and controlling such intermittent rotation through a pattern mechanism. For that purpose I have diagrammatically indicated in Fig. 4 a gearing box 30' wherein are suitably mounted 105 gears for rotating said shafts 29. Movement of continuous rotation is imparted to the gearing in said box by a gear 31 upon a shaft 32 indicated in Figs. 4 and 5, said shaft being driven through gearing herein- 110 after described. 115

In order to release the drop wires upon the bars 28, I preferably provide release key rods (not herein shown), the rotation whereof is controlled by suitable pattern mecha- 120 125 130

nism. The release key rods extend through openings in the drop wires in the general manner disclosed in the said patent to Lea, No. 1,153,869, whereby at suitable 5 times drop wires are released and are delivered to the worms 30.

The pattern mechanism is diagrammatically indicated at 33 in Fig. 5, and is so constructed and arranged that the release 10 key rods may be operated in any combination or sequence or variable order that is desired, thereby to release drop wires from any bar 28, to the feeding action of the feed worms 30. For example, the said shafts and 15 the warp worm shafts hereinafter described and which are also controlled by the pattern mechanism, may be operated in a repeated sequence to present warp threads and drop wires to the needle or a plurality of threads 20 may be presented by one worm shaft followed by the presentation of a plurality of threads by another worm shaft, or the said worm shafts, or any two of them, may be operated simultaneously to present threads to 25 the needle so that two warp threads would be drawn in at the same time. The feeding of warp threads from each warp support or carriage is independent of the feeding of warp threads from the other warp support 30 or carriage, and the same is true of the releasing of the drop wires as well as of the heddles, hereinafter referred to.

In the disclosed embodiment of the invention, I provide a plurality and herein specifically a pair of independent warp supporting means or carriages which are independently traversed through the machine. I effect the independent automatic control of the said two warp supports or carriages and 40 I preferably also provide for the hand control of either of said carriages and, as herein disclosed, in a selective manner, and as above stated I provide for the pattern control of the individual warp threads of the said 45 carriages. These purposes and objects of my invention may be effected in many different ways. I shall without in any way limiting myself thereto proceed to describe the selected embodiment of means for effecting the 50 desired result.

Referring more particularly to Figs. 1 and 6, I have herein represented two warp beams 34, 35, the warp threads 36 from the beam 34 passing through a suitable two-part 55 clamp 37 mounted for sliding movement longitudinally of the machine in two bifurcated guides 38 provided in suitable brackets 39, one at each end of the machine and supported upon the end uprights of the framing. The warp threads 36 extend from the clamp 37 to and about a warp worm 40 and thence to a second two-part clamp 41. The warp worm 40 is suitably and herein loosely supported at the left hand end of the machine in a bracket 42 as indicated in Figs. 1

and 4, and at the opposite end of the machine is suitably supported for rotative movement imparted thereto in any suitable manner. The said warp worm 40 and the corresponding warp worm for the warp threads supported upon the second warp carriage constitute separating, selecting and feeding mechanism for the individual warp threads. Preferably each warp worm comprises a frusto-conical, fluted portion, 75 which first receives, disentangles and separates the warp threads, and a selective feeding or spacing screw or worm portion by which the threads are presented to the hook of the drawing-in needle 2 successively. 80

The warp threads 35' from the second warp beam 35 pass through the suitable two-part clamp 43 mounted similarly to the clamp 37, in bifurcated guides 44 provided in said brackets 39 at opposite ends of the machine. The said warp threads 42 thence pass about the warp worm 45 supported in general parallel relation to the warp worm 40 and driven in a suitable manner, and from thence said warp threads pass through 90 a two-part clamp 46, said two warp worms 40, 45 being within convenient range of the drawing-in needle.

The two warp worms 40, 45 are each intermittently driven from the main drive shaft 95 4 and the intermittent driving thereof is controlled by pattern mechanism 33 (Fig. 5) whereby said worms 40, 45 are independently rotated. Thus in the disclosed embodiment of my invention I selectively 100 drive through the pattern mechanism the warp worms 40 and 45 and the key releasing shafts for the drop wires, and in addition I also so drive through the control of the pattern mechanism the heddle selecting elements, as hereinafter set forth.

In the disclosed embodiment of the invention which is adapted to operate upon two warps, I have provided an independent support or carriage mechanism for each 110 warp. Herein the warp clamps 37 and 41 constitute the support or carriage mechanism for one warp and the clamps 43 and 46 constitute the support or carriage mechanism for the other warp, although the clamps of 115 each support are structurally distinct. Any suitable means may be provided whereby independently and if desired differentially with respect to each other and (or) with respect to the traverse of the needle carriage, the two pairs of clamps, that is, the two supports or carriage mechanisms may be traversed along the machine. Preferably, however, I have provided, as previously stated, the two cams 17, 18 upon the lead 120 screw cam shaft 16. If desired, said cams may be of any desired extent, contour and shape to effect a differentiation in speed of the feed of the two warp supports or carriages with respect to each other. 125 130

The term differential in its several variations is employed in this case to mean movements at different rates. I employ, as elsewhere set forth, hand means for effecting a compensating movement which is in the nature of a movement continuously counteracting momentary variations in thread spacing. I therefore, as herein disclosed, provide a differential movement which is preferably automatic and also provide a compensating movement which is preferably a manual one.

In order to convey motion from the said cams 17, 18 to the said two carriage mechanisms, I have herein provided the following co-acting instrumentalities, to which, however, my invention is in no wise limited.

Upon a stud 47, shown most clearly in Figs. 7 and 8, are independently pivoted two levers 48, 49, either or both of which may be held out of action by latches, one of which is indicated at 49' in Fig. 7. These levers are provided with projections 49" which are adapted to be held against the cams 17, 18 by springs 49''. To the upper slotted ends of said levers 48, 49 are adjustably secured links or rods 50, 51, the outer ends of which are pivotally connected at 52, 53 (Fig. 6) to levers 54, 55, rigidly mounted upon pins 56, 57, each pivoted in a second arm 58, 59, pivotally mounted upon stud 60, 61 extending from the framing. These studs have loosely mounted thereon worms 62, 63, carrying or having integral therewith ratchets 64, 65 which are engaged by dogs or pawls 66, 67, fixed upon said pins 56, 57, whereby in the rotation of the said screw shaft 16, the cams 17, 18 impart intermittent and independent rotation to the said worms 62, 63.

The means for imparting rotative movement to each of said worms 62, 63 may be and preferably is similar to or the same as the means disclosed in the said application of Field, Lanning, Hathaway and Blanchard, Serial No. 142,251, (now Patent No. 1,383,195) for imparting rotative movement to the worm disclosed therein, whereby the single warp carriage or support is traversed through the machine.

In order to transmit motion to the clamps 37, 43, from the said worms 62, 63, I have provided each of said clamps with a rack 68, 69 formed upon or attached to the inner face thereof and with the teeth of which said worms 62, 63 respectively mesh, whereby said clamps are independently and if desired differentially with respect to each other and (or) with respect to the needle carriage traversed along the machine, in an automatic manner.

In order that the corresponding clamps 41, 46 constituting portions of said warp carriages, may be traversed along the machine, each in unison with its correspond-

ing clamp 37, 43, I may provide any suitable means. Herein I have mounted each of said clamps 41, 46 in the generally U-shaped brackets 70, 71. As shown most clearly in Fig. 9, each of said brackets has formed or mounted upon the lower face thereof a rack 72, with which mesh worms 74, loose upon stud shafts 76, 77 laterally extending from block 78, 78', mounted for longitudinal sliding movement upon the rods 80, 81 pivotally mounted at 82 in the end brackets 39, it being understood that preferably at each end of the machine, I provide the described means supporting the said clamps 41, 46, the driving means therefor being, however, provided only at one end of the machine. The said rods 80, 81 may be adjusted to any desired angle or inclination in their pivotal supports and clamped in the desired position to secure the proper tensioning and positioning of the warp threads.

In order to convey unison movement to the clamps 37, 41 and clamps 43, 46, I may provide any suitable means, but herein I have shown two endless sprocket chains 83, 84, preferably provided at the left hand end of the machine, viewing Fig. 4, and passing about sprocket gears 85, 86, fast with the said worms 62, 63, and also passing about sprocket gears 87, 88 upon stud shafts 89, 90 mounted in suitable bearings supported upon a stationary shaft or support 91 extending from the frame upright at the left hand end of the machine, as shown most clearly in Fig. 1. Said sprocket chains 83, 84 also pass about idler sprocket pinions 92, 93, the former of which is mounted upon a suitable stud shaft 94 extending from the adjacent end bracket 39 and the latter of which is adjustably mounted upon the respective rod 105

80. Applicant is not limited to the construction or position of parts shown and here described, but has found such construction and positioning thereof to be convenient, effective, etc. Said sprocket chains 83, 84 mesh as shown with sprocket gears 95, 96, respectively fast with the worms 74, whereby the clamps 41, 46 are driven, the said chains 83, 84 also extending about idler sprocket gears 97, 98, each carried by a suitable block adjustably mounted upon the outer ends of said rods 80, 81, and also about suitable idler sprocket pinions 99, 100, mounted upon the adjacent bracket 39, and thus are returned to the respective sprocket gears 85, 86 upon the worms 62, 63.

In this or in any other suitable manner, unison movements are imparted to the clamp 37 and the clamp 41, constituting or comprising a portion of one warp carriage, and are also imparted to the clamps 43, 46, constituting or comprising a portion of the other warp carriage.

In the disclosed embodiment of my invention, the upper and lower clamps of the

respective carriages are not mounted or held in a common housing or member, but they are operatively connected so as respectively to move together and thereby constitute portions of the respective warp supports or carriages.

In addition to the independent automatic control of the plurality of warp supports or carriages, I preferably provide for a selective hand control of either of said warp supports or carriages, and preferably whereby such hand control may be exercised first upon one and then upon the other of said warp supports or carriages, or in any desired order.

For this purpose I have herein represented as pivotally mounted at 101 at each end of the machine upon the frame upright a lever arm 102, herein represented as having pivotally connected thereto intermediate its ends a link 103 pivotally connected at its upper end at 104 to a lever arm 105 itself pivoted at 106, thereby providing parallel motion means to effect and secure the proper movement of said lever arms 102. The outer free end of each lever arm 102 is provided with a transverse slot 107 having loosely mounted therein a shaft 108 having splined thereon a pinion 109 (Fig. 6) adapted to mesh with either a pinion 110 fast with the sprocket 87 or with a pinion 111 fast with the sprocket 88, the construction being such that the pinion 109 remains in mesh with whichever pinion 110 or 111 it is manually brought into engagement. The pinion 109 is, as stated, splined upon the shaft 108 whereby said pinion may remain in mesh with either the pinion 110 or the pinion 111 while permitting longitudinal movement of said shaft 108, preferably manually; thereby to control the clutch mechanism of the machine in a manner similar to that disclosed in the patent to Hathaway and Lea, No. 1,169,087, dated January 18, 1916. In this manner the machine may be stopped or started by the operator wherever he may be standing between the ends thereof. I have herein represented the said shaft 108 in Fig. 3, which is preferably formed as a tubing and having a plug swivelled therein and bifurcated or vertically slotted at 112 as in the patent to Hathaway and Lea, No. 1,188,070, June 20, 1916, for the passage, as indicated in dotted lines, of the upper curved portion 113 of the upright lever 114 pivoted at 115 and operatively connected in a manner not herein necessary more fully to describe with the clutch 6 of the machine.

When it is not desired to impart hand adjustment to either warp support or carriage, the shaft 108 may be swung into an elevated or non-active position by a movement of the lever arms 102 upwardly, the latter being then supported in such non-

active position by any suitable latch or other means not herein shown and not herein necessary more fully to describe but which may be similar to the latch 49' in Fig. 7.

I may, if desired, provide means manually to drive the main drive shaft 4 and the various parts controlled thereby. For this purpose and as shown most clearly in Figs. 1, 2 and 3, I have provided a longitudinally extending shaft 116 mounted in suitable bearings 117, 117' and having if desired one or more hand wheels 118 to effect more ready rotative movement of said shaft. If desired, clutch or other means 118' (Fig. 2) may be provided to prevent rotation of the shaft 116 in the wrong direction. At the left hand end of said shaft I have provided a bevel gear 119 meshing with a similar gear 120 upon an inclined shaft 121 extending in a downward direction into proximity to the main drive shaft 4, where similar beveled gears (not herein shown) are provided operatively to connect said shafts. By disconnecting the main power drive, the entire machine may be driven manually through the said shaft 116.

The machine herein disclosed may be and preferably is provided with means whereby the desired heddles of the various groups of heddles may be selected and positioned for the passage therethrough of the drawing-in needle. In Fig. 4, I have indicated six heddle selecting shafts 122 each provided with a worm 123 of the general construction shown in the patent to Lea, No. 1,153,869, and in that to Millard F. Field, No. 755,861, the said worms and their shafts being controlled in operation by the pattern mechanism already described.

It is evident that one of the warp beams 34, 35 may carry the bulk of the warp threads and the other may carry a smaller number of threads, or that there may be any suitable distribution of the threads thereon. For example, the arrangement may be such that ten threads may be selected from one warp beam, and then one thread might be selected from the other, thereby arranging the threads for producing a woven-in stripe effect. The threads on one beam may be of a different size from those on the other or of a different character, or they may be differentiated therefrom in any desired manner.

The bars 28, as previously stated, may be loom bars whereon in the weaving operation the drop wires are supported, or they may be special bars to which for the drawing-in operation the drop wires are transferred. The said bars 28 are preferably supported at one end in a clamp 122' indicated in Fig. 4, the other ends of said bars being preferably loosely supported in a suitable bracket 122" (Fig. 2) on the gear box 30'. I prefer-

ably provide a carriage 123' similar in general construction to that shown in the patent to Lea, No. 1,153,869, and by means of which the several series of drop wires may 5 be held with suitable pressure against their respective releasing keys, so that when released they are immediately discharged into the drop wire feed worms. The said carriage is slideable along a suitable track or 10 support 124 (Fig. 2), not herein necessary more fully to describe.

It will be evident from the foregoing description that for each of the two sets of warp threads, I have provided two clamps, 15 the clamps for each set of warp threads being automatically traversed longitudinally of the machine and the two sets of clamps for the two sets of warp threads being if desired traversed longitudinally of the machine 20 at different rates of speed. Selective hand traversing means is provided whereby in any desired order the two sets of warp threads may be moved longitudinally of the machine to effect compensation. Selective 25 mechanism is provided governing the presentation of the threads to the drawing-in needle, two separate warp worms being provided about which the respective warp threads are wrapped. Inasmuch as said warp 30 worms are pattern controlled, it is evident that the threads may be fed to the action of the drawing-in needle in any desired order or sequence. By the pattern mechanism not only are the warp worms selectively controlled, but also the release key shafts 32' 35 and the heddle worms 123, thus permitting any desired selection and drawing-in of the heddles, the drop wires and the warp threads.

40 In the disclosed embodiment of my invention, I have in Figs. 10 and 11 represented six heddle manipulating rods 122 each provided with a worm. The number of these rods, of course, may be varied in different machines. Each of said rods is rotated at 45 the call of the pattern mechanism. In Figs. 10 and 11, I have represented the reed opener shaft 126, this being also rotated in accordance with the call of the pattern in a 50 manner not herein necessary more fully to describe. The release key rods are also rotated at the call of the pattern as well as the two warp worms 40, 45. In the disclosed embodiment of the invention, however, the 55 rods carrying the drop wire feed worms 30 are continuously rotated. I have already stated that the rods for the said drop wire feed worms 30 extend into a gear box 30'. The gear box 30' has positioned therein upon 60 each of the drop wire feed worm rods pinions connected in rotation. The rod whereon is mounted one of said pinions extends through the gear box 30' and has fast upon its outer end a pinion that meshes with 65 the spur gear 31 on the shaft 32. As most

clearly shown in Fig. 10 the shaft 32 has at its right hand end a bevel pinion 128 meshing with a similar pinion 129 upon a shaft 130 extending transversely of the machine and mounted in suitable bearings 131 upon the gear head 132. Upon the other end of the transverse shaft 130 is a bevel pinion 133 meshing with a similar pinion 134 upon a short shaft 135 mounted in the gear head. The shaft 135, as most clearly shown in Fig. 75 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370

The gear 141 on the shaft 142 meshes with a gear 144 fast upon a shaft 145 as most clearly shown in Fig. 11, and said gear 144 meshes with and drives a pinion 146 upon a shaft 147. By reason of the Geneva like stop motion 148, 149, the gear 150 upon the shaft 151 is intermittently rotated. Said gear 150 meshes with and intermittently rotates a pinion upon the reed opener shaft 126, but as indicated in Fig. 10 the rotation of said reed 95 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370

The gear 150 also meshes with and drives a gear 153 upon a shaft 154 that meshes with a pinion 155 upon one of the harness rods 122, whereby the entire train of six harness rods is suitably driven. In order to prevent back lash, I have herein represented the gear 153 as meshing with a larger gear 156 upon a shaft 157, said gear 156 meshing with one of the pinions 155 of the harness rods. The rotation of said harness rods is, however, subject to the call of the pattern as heretofore stated.

As shown most clearly in Fig. 10, the transverse shaft 130 has thereon a spiral gear 159, meshing with a similar and smaller gear 160 upon a short shaft 161 extending longitudinally of the machine. Said shaft 161 is therefore continuously rotated from the main drive shaft of the machine through the said transverse shaft 130 and the described connection therefrom to the said main drive shaft. Upon said constantly rotated shaft 161, as shown most clearly in Fig. 11, is a pinion 162 meshing with a gear 163, which meshes with and drives the pinions 164, 165, upon the shafts 164', 165' of the warp worms 40, 45. The rotation of said warp worm shafts is, however, controlled by the call of the pattern.

As most clearly shown in Fig. 11, the gear head 132 is provided with a base 166 having depending flanges 167 with inwardly extending bars 168 taking under the flanges 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370

169 upon the framing of the machine. The bars 168 are rigidly connected with said gear head and also with the needle carriage whereby the gear head and needle carriage 5 move in unison and as one member through the machine. The needle carriage carries the warp worms 40 and 45 with it in its travel in the usual or any suitable way. The gear box 30' is connected in the well-known 10 or any suitable manner to travel with the needle carriage 3 and the gear head 132.

The inner ends of the release key rods are removably received in chucks 32' (Fig. 4) 15 upon shafts extending through the gear box 30'. Said shafts have upon their opposite ends universal joints which are connected to the shafts 170, shown in Fig. 10. As most clearly shown in Fig. 10, the opposite end of said shafts 170 have universal joints 171 20 connected to the shafts 172, the rotation of said shafts 172 being controlled by the call of the pattern. On the shafts 172 are intermeshing pinions 158 (Figs. 10 and 11), one of which meshes with the adjacent pinion 155.

Thus from the foregoing description, it will be evident that the rotation of the reed 30 opener, the harness control rods, the release key rods and the warp worm rods or shafts 35 is controlled by the call of the pattern.

The pattern mechanism may be of any suitable character. It is shown in greatest detail in Fig. 10.

The pattern mechanism need not be described in detail, inasmuch as in its preferred form, it is like or substantially like that shown in the said co-pending application of La Chance and Pennell (now Patent No. 1,317,924), like that disclosed in the 40 application of Charles Lea, Serial No. 692, 468 (now Patent No. 1,417,078, dated May 23, 1922), and like that shown in the patent to Hathaway and Lea, No. 1,169,087, January 18, 1916.

45 It is sufficient to state that the pinions shown in Fig. 11 are adapted to be clutched to their shafts to rotate the latter at the times desired. Said clutches are controlled by spring pressed rods and a pattern mechanism. Said pattern mechanism is herein represented as comprising a cylinder having perforations adapted to be brought into registration with a row of feeler bars, each having an intervening blank or separating 50 washer. With each retraction of the drawing-in needle, the clutches of the pattern mechanism are thrown into engagement to connect the driving devices of the worm shafts therewith, but are immediately released unless held by the interposition of a 55 washer in the path of a plunger rod.

Having thus described one illustrative embodiment of my invention, I desire it to be understood that although specific terms 60 are employed, they are used in a generic

and descriptive sense and not for purposes of limitation, the scope of the invention being set forth in the following claims.

Claims:

1. A warp-drawing machine, having, in combination, drawing-in mechanism, two warp carriages for supporting a plurality of groups of warp threads and respectively mounted for traversing movement, and automatic traversing means combined with compensating means for said carriages. 70

2. A warp-drawing machine having, in combination, drawing-in mechanism, means to traverse the same, two warp carriages for supporting a plurality of groups of warp threads and respectively mounted for traversing movement, and automatic traversing means combined with compensating means for said carriages. 80

3. A warp-drawing machine having, in combination, drawing-in mechanism, warp carriages for supporting a plurality of groups of warp threads respectively mounted for traversing movement, and automatic traversing means for said carriages combined with compensating means for either of said carriages. 90

4. A warp-drawing machine having, in combination, drawing-in mechanism, means to traverse the same, two warp carriages for supporting a plurality of groups of warp threads and respectively mounted for traversing movement, and automatic traversing means for said carriages combined with compensating means for either of said carriages. 95

5. A warp-drawing machine having, in combination, drawing-in mechanism, a carriage therefor, means to traverse said carriage, two warp carriages for supporting a plurality of groups of warp threads and respectively mounted for traversing movement, and automatic traversing means for said carriages, combined with hand controlled compensating means for either of said carriages. 105

6. A warp-drawing machine having, in combination, drawing-in mechanism, warp carriages for supporting a plurality of groups of warp threads respectively mounted for separate traversing movement, and automatic traversing means for said carriages, in combination with selective hand controlled compensating means for said carriages. 115

7. A warp-drawing machine having, in combination, drawing-in mechanism, means to traverse the same, two warp carriages for supporting a plurality of groups of warp threads respectively mounted for separate traversing movement, and automatic traversing means for said carriages combined with selective hand controlled compensating means for said carriages. 125

8. A warp-drawing machine having, in 130

- combination, drawing-in mechanism, warp carriages for supporting a plurality of groups or warp threads respectively mounted for separate traversing movement, and 5 automatic traversing means for said carriages and compensating means therefor, combined with thread selecting devices for the threads of one of said groups of warp threads.
- 10 9. A warp-drawing machine having, in combination, drawing-in mechanism, means to traverse the same, two warp carriages for supporting a plurality of groups of warp threads respectively mounted for 15 separate traversing movement, and automatic traversing means for said carriages and compensating means therefor, in combination with thread selecting devices for the threads of one or the other of said groups 20 of warp threads.
- 10 10. A warp drawing machine having, in combination, drawing-mechanism, a carriage therefor, means to traverse said carriage, two warp carriages for supporting a plurality of groups of warp threads and 25 respectively mounted for separate traversing movement, and automatic traversing means for said carriages and compensating means therefor, in combination with thread 30 selecting devices for the threads of one or the other of said groups of warp threads.
11. A warp-drawing machine having, in combination, drawing-in mechanism, warp carriages for supporting a plurality of groups of warp threads respectively mounted for 35 separate traversing movement, and automatic traversing means for said carriages and compensating means therefor, in combination with pattern controlled means 40 for the independent threads of one or both of said groups of warp threads.
12. A warp-drawing machine having, in combination, drawing-in mechanism, means to traverse the same, two warp carriages for 45 supporting a plurality of groups of warp threads respectively mounted for separate traversing movement, and automatic traversing means combined with compensating means for said carriages together 50 with pattern control means for the independent threads of one or both of said groups of warp threads.
13. A warp-drawing machine having, in combination, drawing-in mechanism, warp carriages for supporting a plurality of groups of warp threads respectively mounted for 55 separate traversing movement, and automatic traversing means and compensating means for said carriages in combination 60 with selective mechanism governing the presentation of threads from said groups of warp threads.
14. A warp-drawing machine having, in combination, drawing-in mechanism, means to traverse the same, two warp carriages 65 for supporting a plurality of groups of warp threads respectively mounted for separate traversing movement, and automatic traversing means with compensating means for said carriages, in combination with selective mechanism governing the presentation of threads from said groups of warp threads.
15. A warp-drawing machine, in combination, drawing-in mechanism, two warp carriages for supporting a plurality of groups of warp threads respectively mounted for 70 separate traversing movement, and selective mechanism governing the presentation of threads from said groups of warps.
16. A warp-drawing machine having, in combination, drawing-in mechanism, two warp carriages for supporting a plurality of groups of warp threads respectively mounted for 75 separate traversing movement, heddle selectors, and selective mechanism governing the action of said heddle selectors.
17. A warp-drawing machine having, in combination, drawing-in mechanism, two warp carriages for supporting a plurality of groups of warp threads respectively mounted for 80 separate traversing movement, drop-wire handling devices, and selective mechanism governing the operation of said drop wire handling devices.
18. A warp-drawing machine having, in combination, drawing-in mechanism, two warp carriages for supporting a plurality of groups of warp threads respectively mounted for 85 separate traversing movement, heddle selectors, and selective mechanism governing the presentation of threads from the warps and the action of said heddle selectors.
19. A warp-drawing machine having, in combination, drawing-in mechanism, two warp carriages for supporting a plurality of groups of warp threads respectively mounted for 90 separate traversing movement, drop-wire supporting means, and selective mechanism governing the presentation of threads from the warps and the presentation of said drop wires.
20. Textile mechanism comprising, in combination, thread selecting mechanism, two warp carriages respectively mounted for traversing movement, automatic traversing means combined with compensating means for said carriages, and selective mechanism to govern the presentation of threads from the warps.
21. A warp-drawing machine having, in combination, thread selecting mechanism, two warp carriages respectively mounted for 115 traversing movement, automatic traversing means combined with compensating means for said warp carriages, heddle se-
- 100
105

125

- lectors, and selective mechanism governing the presentation of threads from the warps and the action of said heddle selectors.
22. Textile mechanism comprising, in combination, thread selecting mechanism, means to support two sections of warp for respective traversing movement, and automatic traversing means with compensating means for said warp supports, at least one warp support being composed of two sets of clamps having distinct supports.
23. Textile mechanism comprising, in combination, thread selecting mechanism, means to support two sections of warp for traversing movement, and automatic traversing means with compensating means for said warp supports, both of said warp supports being composed of two sets of clamps having distinct supports.
24. A warp-drawing mechanism having, in combination, drawing-in mechanism, means to traverse the same, means to support two sections of warp for traversing movement, and automatic traversing means with compensating means for said warp supports, at least one of said warp supports being composed of two sets of clamps having distinct supports.
25. Textile mechanism comprising, in combination, thread selecting mechanism, means to support two sections of warp for traversing movement, and automatic traversing means with compensating means for said warp supports, at least one warp support being composed of two sets of clamps having distinct supports in combination with means to move the respective sets of clamps.
26. Textile mechanism, comprising, in combination, thread selecting mechanism, means to support two sections of warp for traversing movement, and automatic traversing means combined with compensating means for said warp supports, both of said warp supports being composed of two sets of clamps having distinct supports in combination with means to move the respective sets of clamps.
27. A warp-drawing machine having, in combination, drawing-in mechanism, means to traverse the same, means to support two sections of warp for traversing movement, and automatic traversing means combined with compensating means for said warp supports, at least one of said warp supports being composed of two sets of clamps having distinct supports in combination with means to move the respective sets of clamps.
28. A warp-drawing machine having, in combination, a drawing-in needle, a carriage therefor, means to traverse said carriage, two warp carriages to support a plurality of groups of warp threads mounted for traversing movement, automatic traversing means combined with compensating means for one of said warp carriages, and means to move the other warp carriage.
29. A warp-drawing machine having, in combination, drawing-in mechanism, two warp carriages to support a plurality of groups of warp threads mounted for traversing movement, a warp form for the warp threads of each of said carriages, and automatic traversing means combined with compensating means for said carriages.
30. The combination of a drawing-in device, two separate carriages for supporting a plurality of groups of warp threads, thread selecting devices for the groups disposed in substantially unvarying spacial relation to said drawing-in device, and means for operating said devices selectively to present threads to the drawing-in device.
31. In a textile machine, the combination with two separate carriages for holding a plurality of sets of warp threads, of a plurality of thread selectors, one for each set, arranged each for relative travel across the threads of its set, mechanism for causing the progressive engagement and selection of the threads of each set by its thread selector, the selectors being actuated in independently timed relation, and a thread placing device common to the selectors for engaging threads selected thereby from one or the other of said carriages.
32. In a warp drawing-in machine, the combination with two separate carriages for a plurality of separate groups of warp threads respectively mounted for differential traversing movement, harness and reed supports for holding the reed, means to support a plurality of harnesses in a generally parallel relation to the threads, and operating mechanism adapted for relative travel across the threads and said harnesses and reed, said operating mechanism including thread separating means for each group and a common drawing-in device.
33. In a textile machine, the combination with two distinct carriages for supporting a plurality of groups of warp threads, operating mechanism for progressively acting upon the successive threads of each group, said mechanism including a rotary screw selector for the threads of each group and thread placing mechanism, and mechanism selectively to actuate said selectors.
34. In a textile machine, the combination with distinct carriages for holding distended two separate groups of warp threads respectively mounted for differential traversing movement, thread selecting mechanism for each group, and means to operate said mechanism to select the thread first from one group and subsequently a thread from the other group, and thread placing mechanism to take the selected threads.
35. In a drawing-in machine, the combination with two distinct carriages for hold-

- ing distended a plurality of separate groups of warp threads respectively mounted for differential traversing movement, harness supports, a thread separator for each group 5 of warp threads, a drawing-in device to put a warp thread through a harness eye, and means for causing the progressive action of the drawing-in device and thread separators on the warp threads.
- 10 36. A warp-drawing machine having, in combination, drawing-in mechanism, warp carriages for supporting a plurality of groups of warp threads and mounted for traversing movement, and automatic traversing means combined with compensating means for said carriages in combination with means for supporting one or more banks of drop wires, and means for presenting said drop wires to the action of said 15 drawing-in mechanism.
37. A warp-drawing machine having, in combination, drawing-in mechanism, means to traverse the same, two warp carriages for supporting a plurality of groups of warp threads mounted for traversing movement, and automatic traversing means combined with compensating means for said carriages in combination with means for supporting one or more banks of drop wires and means 20 for presenting said drop wires to the action of said drawing-in mechanism.
38. A warp-drawing machine having, in combination, drawing-in mechanism, warp carriages for supporting a plurality of 25 groups of warp threads mounted for traversing movement, and automatic traversing means combined with compensating means for said carriages, together with means for supporting a plurality of banks of drop 30 wires and means for selectively presenting said drop wires to the action of said drawing-in mechanism.
39. A warp-drawing machine having, in combination, drawing-in mechanism, means to traverse the same, two warp carriages for supporting a plurality of groups of warp threads mounted for traversing movement, and automatic traversing means and compensating means for said carriages, in combination with means for supporting a plurality of banks of drop wires and means for selectively presenting said drop wires to the action of said drawing-in mechanism.
40. A warp-drawing machine having, in combination, thread selecting mechanism, two warp carriages on the same side of said mechanism mounted for traversing movement, automatic traversing means, and compensating means for said carriages in combination with means for supporting a plurality of banks of drop wires and means for selectively presenting said drop wires to the action of said thread-selecting mechanism.
41. A warp-drawing machine having, in combination, two distinct thread separating devices, a drawing-in device, two warp carriages for supporting a plurality of groups of warp threads to be respectively drawn in by said device, and automatic differential traversing means for both of said carriages.
42. A warp-drawing machine having, in combination, two distinct thread separating devices, a drawing-in device, means to traverse the same, two warp carriages for supporting a plurality of groups of warp threads to be respectively separated by said devices and automatic differential traversing means for both of said carriages.
43. A warp-drawing machine having, in combination, two distinct thread separating devices, a drawing-in device, two warp carriages on the same side of said devices, and automatic differential traversing means for both of said carriages.
44. A warp-drawing machine having, in combination, two distinct thread separating devices, a drawing-in device, means to traverse the same, two warp carriages on the same side of said devices, and automatic differential traversing means for both of said carriages.
45. Textile mechanism comprising, in combination, a drawing-in needle, two warp carriages composed, respectively, of sliding clamps 37, 41, and 43, 46, gearing for moving the clamps of each set in unison and worms 62, 63, for sliding said clamps.
46. Textile mechanism comprising, in combination, a drawing-in needle, two warp carriages composed, respectively, of sliding clamps 37, 41, and 43, 46, gearing for moving the clamps of each set in unison, worms 62, 63 for sliding said clamps, and means for imparting differential movement to said worms.
47. Textile mechanism comprising, in combination, a drawing-in needle, two warp carriages composed, respectively, of sliding clamps 37, 41, and 43, 46, sprocket chain mechanism for moving the clamps of each set in unison, and means for driving said sprocket chains.
48. Textile mechanism comprising, in combination, a drawing-in needle, two warp carriages composed, respectively, of sliding clamps 37, 41, and 43, 46, sprocket chain mechanism for moving the clamps of each set in unison, and means for imparting differential movement to the two sets of clamps.
49. Textile mechanism comprising, in combination, a drawing-in needle, two warp carriages composed, respectively, of sliding clamps 37, 41, and 43, 46, sprocket chain mechanism for moving the clamps of each set in unison, and hand-control means for driving one or both of said sprocket chains.
50. A warp-drawing machine having, in combination, drawing-in mechanism, warp carriages for supporting a plurality of

- groups of warp threads, and automatic traversing means for said carriages combined with hand controlled compensating means for at least one of said carriages.
5. 51. Textile mechanism comprising, in combination, thread selecting mechanism, two warp carriages on the same side of said thread selecting mechanism mounted for traversing movement, automatic traversing means combined with compensating means for one of said carriages, and means to move the other warp carriage.
10. 52. Textile mechanism comprising, in combination, thread selecting mechanism, two warp carriages on the same side of said thread selecting mechanism mounted for traversing movement, automatic traversing means combined with compensating means for one of said carriages, and means to move the other warp carriage, said thread selecting mechanism being constructed to select threads from one or the other of said two warp carriages.
15. 53. A warp-drawing machine having, in combination, thread drawing-in mechanism, means to support two sections of warp, and automatic traversing means combined with compensating means for said warp supports, at least one warp support being composed of two sets of clamps having distinct supports.
20. 54. Textile mechanism comprising, in combination, thread drawing-in mechanism, means to support two sections of warp, and automatic traversing means combined with compensating means for said warp supports, both of said warp supports being composed of two sets of clamps having distinct supports.
25. 55. Textile mechanism comprising, in combination, thread selecting means, means to support two sections of warp including two clamps for each set of warp threads, means to traverse said clamps along the mechanism, and means to change the plane along which at least one of said clamps traverses the machine.
30. 56. Textile mechanism comprising, in combination, thread selecting mechanism, means to support a section of warp and including two clamps, means to traverse said clamps along the machine, and means to change the plane of traverse of one of said clamps.
35. 57. A warp-drawing machine having, in combination, drawing-in mechanism, a plurality of warp carriages for supporting a corresponding plurality of groups of warp threads and respectively mounted for traversing movement, and automatic traversing means for said carriages.
40. 58. A warp-drawing machine having, in combination, drawing-in mechanism, two warp carriages to support a plurality of groups of warp threads for traversing movement, automatic traversing means combined with compensating means for one of said warp carriages, and means to move the other warp carriage.
45. 59. Textile mechanism comprising, in combination, thread selecting mechanism, two warp carriages on the same side of said thread selecting mechanism and respectively mounted for traversing movement, and automatic traversing means combined with compensating means for said carriages.
50. 60. Textile mechanism comprising, in combination, thread selecting mechanism, means to traverse the same, two warp carriages on the same side of said thread selecting mechanism and respectively mounted for traversing movement, and automatic traversing means combined with compensating means for said carriages.
55. 61. Textile mechanism comprising, in combination, thread selecting mechanism, a carriage therefor, means to traverse said carriage, two warp carriages on the same side of said thread selecting mechanism and respectively mounted for traversing movement, and automatic traversing means combined with compensating means for said warp carriages.
60. 62. In a warp replenishing machine, a carriage to support a transverse section of a warp with the threads thereof distended in parallel arrangement, a carriage to support a second transverse section of a warp with the threads thereof distended in parallel arrangement, a third carriage, thread selecting means supported on said third carriage to work successively upon said threads, one main power means, and power driven means operatively connected to said one main power means and to all of said carriages to move all of said carriages from said one main power means, the said power driven means including means to move said three carriages longitudinally of the machine, and also including means to give to said first and second mentioned carriages and their contained threads feeding movements differentially related to the feeding movement of said third mentioned carriage.
65. 63. In a machine for operating upon warp threads, the combination with a main frame, of a carriage to support a transverse section of a warp with the threads thereof distended in parallel arrangement, a second carriage to support another transverse section of a warp with the threads thereof distended in parallel arrangement, a third carriage, thread selecting mechanism supported upon said third carriage to work successively upon said threads, one main power means, and power driven means operatively connected to said one main power means and to all of said carriages to move all of said carriages from said one main power means, said power driven means including means to move said third mentioned carriage.

- riage transverse the warp threads and lengthwise the machine frame, said power driven means also including step-by-step feed means to give to said first and second mentioned carriages and their contained threads feeding movements differentially related to the feeding movement of said third mentioned carriage.
64. In a warp replenishing machine, a carriage to support a transverse section of a warp with the threads thereof distended in parallel arrangement, a second carriage, thread selecting mechanism supported thereon to work successively upon said threads, one main power means, and power driven means operatively connected to said one main power means and to said carriages to move both of said carriages from said main power means, said power driven means including means to move said second carriage longitudinally of the machine and also including means to give to said first mentioned carriage and its contained threads a feeding movement differentially related to the feeding movement of said second mentioned carriage, in combination with a third carriage to support a second transverse section of a warp with the threads thereof distended in parallel arrangement.
65. In a machine for operating upon warp threads, the combination with a main frame, of a carriage to support a transverse section of a warp with the threads thereof distended in parallel arrangement, a movable operating carriage, thread selecting mechanism supported thereon to work successively upon said threads, one main power means, and power driven means operatively connected to said one main power means and to said carriages to move both of said carriages from said one main power means, said power driven means including means to move said second mentioned carriage transverse the warp threads, lengthwise the machine frame, said power driven means also including step-by-step feed means to give to said first mentioned carriage and its contained threads a feeding movement differentially related to the feeding movement of said second mentioned carriage, in combination with a third carriage to support a second transverse section of a warp with the threads thereof distended in parallel arrangement.
66. In a warp replenishing machine, a carriage to support a transverse section of a warp with the threads thereof distended in parallel arrangement, a second carriage to support a second transverse section of a warp with the threads thereof distended in parallel arrangement, a third carriage, drawing-in mechanism supported on said third carriage to work successively upon said threads, one main power means and power driven means operatively connected to said one main power means and to each of said carriages to move all of said carriages from said one main power means, said power driven means including means to move said third carriage transverse the machine and also including means to give to said first and second mentioned carriages and their contained threads feeding movements differentially related to the feeding movement of said third mentioned carriage.
67. In a warp replenishing machine, a carriage to support a transverse section of a warp with the threads thereof distended in parallel arrangement, a carriage to support a second transverse section of a warp with the threads thereof distended in parallel arrangement, a third carriage, thread selecting means supported on said third carriage to work successively upon said threads, one main power means, and power driven means operatively connected to said one main power means and to all of said carriages to move all of said carriages from said one main power means, the said power driven means including means to move said three carriages longitudinally of the machine, and also including means to give to said first and second mentioned carriages and their contained threads feeding movements differentially related to the feeding movement of said third mentioned carriage, in combination with compensating means for either of said warp carriages.
68. In a machine for operating upon warp threads, the combination with a main frame, of a carriage to support a transverse section of a warp with the threads thereof distended in parallel arrangement, a second carriage to support another transverse section of a warp with the threads thereof distended in parallel arrangement, a third carriage, thread selecting mechanism supported upon said third carriage to work successively upon said threads, one main power means, and power driven means operatively connected to said one main power means and to all of said carriages to move all of said carriages from said one main power means, said power driven means including means to move said third mentioned carriage transverse the warp threads lengthwise the machine frame, said power driven means also including step-by-step feed means to give to said first and second mentioned carriages and their contained threads feeding movements differentially related to the feeding movement of said third mentioned carriage, in combination with hand-controlled compensating means for either of said warp carriages.
69. In a warp replenishing machine, a carriage to support a transverse section of a warp with the threads thereof distended in parallel arrangement, a second carriage,

- thread selecting mechanism supported thereon to work successively upon said threads, one main power means, and power driven means operatively connected to said one main power means and to said carriages to move both of said carriages from said main power means, said power driven means including means to move said second carriage longitudinally of the machine and also including means to give to said first mentioned carriage and its contained threads a feeding movement differentially related to the feeding movement of said second mentioned carriage, in combination with a third main power means and to said carriages to move both of said carriages from said main power means, said power driven means including means to move said second carriage longitudinally of the machine and also including means to give to said first mentioned carriage and its contained threads a feeding movement differentially related to the feeding movement of said second mentioned carriage, in combination with a third carriage to support a second transverse section of a warp with the threads thereof distended in parallel arrangement, in combination with hand-controlled compensating means for either of said warp carriages.
70. In a machine for operating upon warp threads, the combination with a main frame, of a carriage to support a transverse section of a warp with the threads thereof distended in parallel arrangement, a movable operating carriage, thread selecting mechanism supported thereon to work successively upon said threads, one main power means, and power driven means operatively connected to said one main power means and to said carriages to move both of said carriages from said one main power means, said power driven means including means to move said second mentioned carriage transverse the warp threads, lengthwise the machine frame, said power driven means also including step-by-step feed means to give to said first
- mentioned carriage and its contained threads a feeding movement differentially related to the feeding movement of said second mentioned carriage, in combination with a third carriage to support a second transverse section of a warp with the threads thereof distended in parallel arrangement, in combination with hand-controlled compensating means for either of said warp carriages.
71. In a warp replenishing machine, a carriage to support a transverse section of a warp with the threads thereof distended in parallel arrangement, a second carriage to support a second transverse section of a warp with the threads thereof distended in parallel arrangement, a third carriage, drawing-in mechanism supported on said third carriage to work successively upon said threads, one main power means and power driven means operatively connected to said one main power means and to each of said carriages to move all of said carriages from said one main power means, said power driven means including means to move said third carriage longitudinally of the machine and also including means to give to said first and second mentioned carriages and their contained threads feeding movements differentially related to the feeding movement of said third mentioned carriage in combination with hand-controlled compensating means for either of said warp carriages.
- In testimony whereof, I have signed my name to this specification.

EDGAR F. HATHAWAY.
